UNITED STATES PATENT OFFICE

NICHOLAS BENENATI, OF NEW YORK, N. Y.

DESIGN FOR A FOOT REST

Application filed September 15, 1931. Serial No. 41,111. Term of patent 3½ years.

To all whom it may concern:

Be it known that I, NICHOLAS BENENATI, a citizen of the United States, and a resident of the city of New York, in the county of New York and State of New York, have invented a new, original, and ornamental Design for Foot Rests, reference being had to the accompanying drawing, forming part thereof.

The figure is a perspective view of a foot rest showing my new design.

I claim:

The ornamental design for a foot rest, as shown.

NICHOLAS BENENATI,
